UNITED STATES PATENT OFFICE

2,363,135

DOOR CONSTRUCTION

Thorvald Madland, Chicago, Ill., assignor to The Youngstown Steel Door Company, Cleveland, Ohio, a corporation of Ohio

Application May 12, 1942, Serial No. 442,699

4 Claims. (Cl. 20—26)

This invention relates to door construction and is directed more particularly to sliding lift doors for railway house cars and to the construction for securing a weather-tight seal for the upper edge thereof.

It is an object of this invention to provide sliding lift doors for railway house cars the upper edge of which shall be so constructed as to furnish a flexible weather-tight seal.

A further object is the provision of doors of the character stated above, the upper edge of which shall be so constructed and related to door headers that a flexible weather-tight seal is secured by a simple flexing action when the doors are lowered.

A further object is to provide doors of the character stated above, the upper edge of which shall incorporate flexible sealing members so related to the doors as to be protected thereby.

Other objects of the invention will become clear as the description thereof proceeds.

In the drawing forming part of this specification:

Fig. 1 is a partial elevation of a sliding lift door and associated car side illustrating the invention, parts being broken away to more clearly show the invention.

Fig. 2 is a horizontal section taken on line 2—2 of Fig. 1.

Fig. 3 is a vertical section taken on line 3—3 of Fig. 1.

Referring to the drawing wherein a preferred embodiment of the invention is illustrated, reference numeral 10 designates the side plate of a side wall of a railway house car. The side plate is usually Z-shaped in section embodying an upstanding flange 11 shown partially in Figs. 1 and 3 of the drawing, a horizontal web 12 and a depending flange 13.

A Z-shaped retaining bar 14 is fastened to the depending flange 13 as by means of rivets 15 which pass through the upstanding leg 16 of the retaining bar. The web 17 of said bar extends outwardly and carries a depending leg 18 spaced from the depending flange 13 of the side plate.

A door header 19 is also fastened to the depending flange 13 of the side plate as by means of rivets 20. The door header extends across the door opening and is substantially J-shaped in section and embodies an inner upstanding flange 21 which is fastened to the depending flange 13 of the side plate by the rivets 20, an outwardly extending web 22 and an upwardly extending flange 23. The header presents a trough 24 capable of catching and disposing of foreign matter which

might otherwise find its way into the car through the door opening. It will be observed from Fig. 3 of the drawing that the upstanding flange 23 of the header is spaced from the depending leg 18 of the retaining bar 14 so as to provide with said leg a guide and retaining construction for a sliding lift door.

The door illustrated is formed of metal and embodies a metallic panel 25 formed with a plurality of horizontal corrugations, the uppermost of which is shown at 26. These corrugations merge at their ends into vertical corrugations 27 and 28 formed in the panel adjacent to the front and rear vertical edges thereof. A substantially channel shaped reinforcing member 29 is secured to the front vertical margin of the door. The rear vertical margin of the door is reinforced by means of a sealing strip 30 and a buffer angle 31. When the door is closed the sealing strip 30 is adapted to cooperate with a spark strip 32 to seal the rear edge of the door. The spark strip 32 is fastened to the outwardly extending leg 33 of an angle member 34 which is secured as by means of rivets 35 to the leg 36 of a door post 37 shown partially in Fig. 2 of the drawing.

While the door has been described in some detail, its construction is well known and it is to be understood that the instant invention is not limited to such a door but may be utilized with doors constructed of different materials and of different designs.

The upper margin of the door is reinforced by means of an angle member 38, the vertical leg 39 of which is secured as by means of rivets 40 upon the outside of the metallic panel 25. The horizontal leg 41 of the reinforcing angle 38 extends inwardly across the upper edge of the panel and the upstanding flange 23 of the door header 19 so as to lie above the trough 24 of said header. It will be observed from Fig. 3 of the drawing that the inwardly extending flange 41 of the reinforcing angle is spaced above the upper edge of the upstanding flange 23 of the door header. The instant invention provides a construction whereby this space is effectively closed so as to prevent any foreign matter, such as dust, cinders, rain, snow, or the like, from being forced out of the trough 24 above the flange 23 and into the car.

The illustrated embodiment of the invention takes the form of a flexible metallic sealing strip 42 which is angular in section. The sealing strip embodies a flange 43 disposed between the outer face of the panel 25 and the vertical leg 39 of the reinforcing angle 38 and frictionally secured between these members by the rivets 40. The

sealing strip 42 also embodies a horizontal flange 44 which bears against the underside of the horizontal flange 41 of the reinforcing angle 39. The flange 44 is formed with a return bend and is extended downwardly and outwardly in the form of a readily flexed flange 45.

The door illustrated on the drawing is of the lift type, that is, a door which in its lowered position is frictionally supported upon a track and which is adapted to be elevated and supported upon rollers or other anti-friction means when it is desired to open or close the door. The door is illustrated in its lowered position in full lines in Fig. 3 of the drawing and in elevated position in dot and dash lines. Any desired means may be provided for effecting elevation and anti-frictional support of the door, an example of such means being shown in the patent to Madland, #2,027,242, granted January 7, 1936.

The sealing strip 42 extends across the door opening and for substantially the width of the door. When the door is elevated the flange 45 is in the position shown in dot and dash lines in Fig. 3 of the drawing. Upon lowering of the door when it reaches its closed position contact between flange 45 and the upstanding flange 23 of the door header 19 is established and as the door continues its lowering movement to frictional engagement with its supporting track flange 45 of the sealing strip is flexed so as to insure sealing engagement thereof with the header flange 23. It will be apparent that when such engagement has been established no foreign matter can be forced out of the header trough 24 over the flange 23 into the car. Any foreign matter which may be in the trough will be disposed of through the end of the trough which is open beyond the spark strip 32 and outwardly of the door opening.

To insure against damage to the sealing strip 42 when the door is being closed the upstanding flange 23 of the header is bevelled, as indicated at 46. This flange is extended rearwardly beyond the attaching flange of the spark strip 32 as more clearly shown in Fig. 1. The sealing strip 42 is similarly extended and its end bevelled as shown in Fig. 2 to avoid interference with the door sealing strip 30 which extends upwardly to the leg 41 of the reinforcing angle 38. The upper rear corner of the door is thereby effectively sealed.

It is apparent that the invention is not limited to the particular shape of the illustrated sealing strip nor to the mode of securement of the sealing strip to the door. In the employment of the instant invention modification of the door structure and car side structure is avoided. The sealing strip does not interfere with interchangeability with doors which may not be provided with such a strip and its disposition is such that it is protected during shipment of the doors and at all other times by the door reinforcing angle.

It will be apparent that numerous changes and modifications in the details of the invention will be clear to those skilled in the art. It is intended, therefore, that all such modifications and changes

be comprehended within this invention, which is to be limited only by the scope of the claims appended hereto.

I claim:

- 5 1. A sliding lift door for railway house cars comprising a panel, a metallic reinforcing member secured to the upper margin of said panel, said member having a vertical flange fastened to the outside of said panel and a flange extending inwardly across the upper edge of said panel, and a flexible metallic sealing strip, said sealing strip having a flange frictionally secured between said panel and said vertical flange of said reinforcing member and a flange abutting the underside of and terminating within said inwardly extending flange of said reinforcing member, said latter flange of said sealing strip having an outwardly and downwardly inclined sealing flange.
- 10 2. In a railway house car embodying a wall having a door opening therein, a trough-shaped door header secured to said wall across said door opening, said header having an outer upwardly extending flange, a longitudinally sliding lift door mounted upon said car, a reinforcing flange at the upper margin of said door extending inwardly above said header flange, a flexible metallic sealing strip secured to said door, said sealing strip having a flange abutting against the underside of said reinforcing flange and a downwardly and outwardly inclined sealing flange, said latter flange overlapping and being engaged and flexed by the upper edge of said header flange when said door is lowered.
- 15 3. In a railway house car embodying a wall having a door opening therein, a trough-shaped door header secured to said wall across said door opening, said header having an outer upwardly extending flange, a longitudinally sliding lift door mounted upon said car, a reinforcing flange at the upper margin of said door extending inwardly above said header flange, a flexible metallic sealing strip secured to said door, said sealing strip having a flange abutting against the underside of said reinforcing flange and having a downwardly inclined sealing flange, said latter flange overlapping and being engaged and flexed by the upper edge of said header flange when said door is lowered.
- 20 4. A sliding lift door for railway house cars comprising a panel, a metallic reinforcing member secured to the upper margin of said panel, said member having a vertical flange fastened to the outside of said panel and a flange extending inwardly across the upper edge of said panel, and a flexible metallic sealing strip, said sealing strip having a flange frictionally secured between said panel and said vertical flange of said reinforcing member, said sealing strip abutting the underside of said inwardly extending flange of said reinforcing member and having a downwardly inclined sealing flange terminating within said inwardly extending flange of said reinforcing member.
- 25 5. A sliding lift door for railway house cars comprising a panel, a metallic reinforcing member secured to the upper margin of said panel, said member having a vertical flange fastened to the outside of said panel and a flange extending inwardly across the upper edge of said panel, and a flexible metallic sealing strip, said sealing strip having a flange frictionally secured between said panel and said vertical flange of said reinforcing member, said sealing strip abutting the underside of said inwardly extending flange of said reinforcing member and having a downwardly inclined sealing flange terminating within said inwardly extending flange of said reinforcing member.
- 30 6. A sliding lift door for railway house cars comprising a panel, a metallic reinforcing member secured to the upper margin of said panel, said member having a vertical flange fastened to the outside of said panel and a flange extending inwardly across the upper edge of said panel, and a flexible metallic sealing strip, said sealing strip having a flange frictionally secured between said panel and said vertical flange of said reinforcing member, said sealing strip abutting the underside of said inwardly extending flange of said reinforcing member and having a downwardly inclined sealing flange terminating within said inwardly extending flange of said reinforcing member.
- 35 7. A sliding lift door for railway house cars comprising a panel, a metallic reinforcing member secured to the upper margin of said panel, said member having a vertical flange fastened to the outside of said panel and a flange extending inwardly across the upper edge of said panel, and a flexible metallic sealing strip, said sealing strip having a flange frictionally secured between said panel and said vertical flange of said reinforcing member, said sealing strip abutting the underside of said inwardly extending flange of said reinforcing member and having a downwardly inclined sealing flange terminating within said inwardly extending flange of said reinforcing member.
- 40 8. A sliding lift door for railway house cars comprising a panel, a metallic reinforcing member secured to the upper margin of said panel, said member having a vertical flange fastened to the outside of said panel and a flange extending inwardly across the upper edge of said panel, and a flexible metallic sealing strip, said sealing strip having a flange frictionally secured between said panel and said vertical flange of said reinforcing member, said sealing strip abutting the underside of said inwardly extending flange of said reinforcing member and having a downwardly inclined sealing flange terminating within said inwardly extending flange of said reinforcing member.
- 45 9. A sliding lift door for railway house cars comprising a panel, a metallic reinforcing member secured to the upper margin of said panel, said member having a vertical flange fastened to the outside of said panel and a flange extending inwardly across the upper edge of said panel, and a flexible metallic sealing strip, said sealing strip having a flange frictionally secured between said panel and said vertical flange of said reinforcing member, said sealing strip abutting the underside of said inwardly extending flange of said reinforcing member and having a downwardly inclined sealing flange terminating within said inwardly extending flange of said reinforcing member.
- 50 10. A sliding lift door for railway house cars comprising a panel, a metallic reinforcing member secured to the upper margin of said panel, said member having a vertical flange fastened to the outside of said panel and a flange extending inwardly across the upper edge of said panel, and a flexible metallic sealing strip, said sealing strip having a flange frictionally secured between said panel and said vertical flange of said reinforcing member, said sealing strip abutting the underside of said inwardly extending flange of said reinforcing member and having a downwardly inclined sealing flange terminating within said inwardly extending flange of said reinforcing member.
- 55 11. A sliding lift door for railway house cars comprising a panel, a metallic reinforcing member secured to the upper margin of said panel, said member having a vertical flange fastened to the outside of said panel and a flange extending inwardly across the upper edge of said panel, and a flexible metallic sealing strip, said sealing strip having a flange frictionally secured between said panel and said vertical flange of said reinforcing member, said sealing strip abutting the underside of said inwardly extending flange of said reinforcing member and having a downwardly inclined sealing flange terminating within said inwardly extending flange of said reinforcing member.
- 60 12. A sliding lift door for railway house cars comprising a panel, a metallic reinforcing member secured to the upper margin of said panel, said member having a vertical flange fastened to the outside of said panel and a flange extending inwardly across the upper edge of said panel, and a flexible metallic sealing strip, said sealing strip having a flange frictionally secured between said panel and said vertical flange of said reinforcing member, said sealing strip abutting the underside of said inwardly extending flange of said reinforcing member and having a downwardly inclined sealing flange terminating within said inwardly extending flange of said reinforcing member.

THORVALD MADLAND.
